UNITED STATES PATENT OFFICE.

ISAAC L. PFAFF, OF DANSVILLE, NEW YORK.

WINDMILL.

SPECIFICATION forming part of Letters Patent No. 379,125, dated March 6, 1888.

Application filed June 29, 1887. Serial No. 242,884. (No model.)

To all whom it may concern:

Be it known that I, ISAAC L. PFAFF, of Dansville, in the county of Livingston and State of New York, have invented certain new and 5 useful Improvements in Windmills; and I do hereby declare that the following is a full, clear, and exact description thereof, reference being had to the accompanying drawings, and to the letters of reference marked thereon, 10 which form part of this specification, in which—

Figure 1 is a side elevation of my improved windmill and vane. Fig. 2 is a top or plan view of the same, showing the vane displaced in dotted lines. Fig. 3 is a vertical central 15 section through the wheels and gearing on line $x-x$, Fig. 2. Fig. 4 is a vertical transverse section on line $y-y$, Fig. 1. Fig. 5 is a view of one of the wheel-hubs detached.

This invention relates to improvements in 20 turbine wind-wheels; and it has for its objects to improve the construction of the wheels, to employ a double pair of oppositely revolving wheels, and which can be employed independently of each other or together to operate the 25 driving shaft of the mill, and to improve the vane thereof so that it will yield quickly to violent gusts of wind, whereby the danger of the mill being blown down by reason of a sudden blast of wind striking the vane and 30 wheels broadside will be obviated.

To these ends the invention consists in the peculiar and novel construction and arrangement of parts hereinafter described, illustrated in the drawings, and particularly specified in 35 the claims hereto appended.

Referring to the drawings by letters, A designates a vertical fixed shaft rising from suitable supports, (not shown in the drawings,) and having a reduced portion, a , near its upper 40 end, and a still more reduced portion, B, above portion a , the junctions of the portions forming shoulders b c , hereinafter referred to.

C designates a hub, preferably of metal, fitted upon portion B of shaft A, and supported 45 thereon by abutting against shoulder c , as shown. This hub is prevented from vertical play by means of a collar and set-screw, D, as shown. From diametrically-opposite points of hub C extend arms or shafts E E, which have 50 shoulders e formed on them near their junction with hub C. The shafts E E stand in line with

each other, and the lateral movement of one shaft E will, through hub C, correspondingly but oppositely move the opposite shaft, so that said shafts will always be diametrically opposite each other on hub C. On one shaft E is a wind-wheel, and on the other shaft is a wheel and vane, as hereinafter described.

F designates a hollow shaft mounted loosely on portion a of shaft A, below hub C, and supported thereon by abutting against shoulder b , or in other suitable manner, so that it can rotate freely thereon. At the upper end of shaft F, just below hub C when the latter is in position, is a bevel-gear, f, by means of 55 which the shaft F is rotated.

G G designate the wind-wheels, which are constructed and mounted on shafts E E as follows:

H designates a spool-shaped hub, provided 70 at its opposite ends with upstanding annular flanges h h , as shown. These flanges h h are radially and angularly slotted, as shown, and in these slots are secured the inner ends of the propeller-shaped blades I I, which are set 75 diagonally across the hubs H, by engaging in different opposite slots in flanges h h , as shown. By reason of the spool shape of hubs H H the blades I I are firmly supported thereby and the weight of the hubs greatly reduced. The 80 wheels G G are constructed similarly, but are placed on the shafts E E on opposite sides of the hub, so that they face in opposite directions—that is, one wheel revolves to the right and the other to the left. On the inner ends 85 or faces of hubs H H are formed or rigidly secured bevel-gears J J, which are adapted to mesh with the gear f and actuate the shaft F. The wheels G, being on opposite sides of wheel f and rotated in opposite directions, will 90 impart the same direction of rotation to shaft F, as is evident. The wheels G G are kept from longitudinal displacement on shafts E E by means of collars K and set-bolts k therein, so that by properly adjusting these collars the 95 gears J can be held in or out of engagement with gear f. The gears J J are prevented from binding on hub C by reason of the shoulders e of shafts E, as shown.

It will be observed that both wheels rotate 100 independently of each other's shaft, and that each revolves on, and not with, its support-

ing-shaft. Consequently I am able to make these parts of my mill much lighter than would be the case if the shafts had to revolve, and thus greatly lighten the weight of the mill and 5 attain a light running or action of the wheels G. The wind, escaping through the front wheel, E, strikes the blade of the inner wheel and revolves the latter, as is evident.

If desired, only one wheel E may be employed in running the mill, the other being disengaged, as described. By this means the mill can be run with more or less power, as may be required.

L designates the vane, which consists of an 15 inner supporting fixed portion, l, and an outer adjustable portion, M, hinged to the outer edge of part l, as shown. The part l is provided centrally and longitudinally with a sleeve, m, which fits over the extended end of one shaft 20 E and secures the vane in position thereon.

On the faces of parts l and M opposite their 25 hinges are arranged the devices for adjusting part M, and thereby throwing the mill into or out of working position, and for regulating its movements in fluctuating winds. These devices are as follows:

N designates a short horizontal bar on part l, playing through a guide, n, thereon and pivoted or hinged at its outer end to an out-standing hinge, O, on part M. The inner end of bar N is connected by a link, o, with a vertical hanging lever, P, about centrally thereof, as shown. This lever P is pivoted to the part l at its upper end, and its lower end 35 passes through a suitable guide or keeper, p, below link o. The lower end of lever P is connected to ropes Q Q, which pass through eyes q q near opposite ends of part l. By means of these ropes and eyes the lever P can 40 be shifted. The outward movement of lever P, acting through its connections upon part M, causes the latter to turn on its hinges and swing to a position at right angles to part l and in line with wheels E E. (Shown in dotted lines, Fig. 2.) When in this position the 45 mill is out of working position, as the wind does not strike the wheels G G properly to actuate them. It is obvious that by retracting lever P the part M of vane L will be brought 50 back to its proper position and the mill be ready for action.

In order to permit the yielding of the vane when subjected to fluctuating winds, and yet hold part M in normal position independently 55 of ropes Q Q, I provide a spring, R, one end of which is fastened to the part l, the other end to part M on the same side of the vane as the adjusting devices. Now, it is obvious that when part M is swung around, as indicated, 60 tension will be put on spring R, and when the displacing power is released the spring will return the part M to proper position. Now,

should the vane be struck broadside by the wind, the part M, which is the larger and main part of the vane, would yield to the wind and 65 relieve the shock and consequent danger to the mill and turn the wheels to face the wind gently and not violently, spring R aiding this action of the vane.

The lower end of shaft F may be provided 70 with suitable gearing or other connecting devices for imparting the force of the mill to the desired machinery.

Having described my invention, I claim—

1. In a windmill, the combination of the 75 fixed shaft carrying a revolute driving-shaft, and a hub above the latter shaft provided with diametrically-opposite arms, with the oppositely-facing wheels mounted on said arms, respectively, and the gearing between the hubs 80 of said wheels and the revolute shaft, all substantially as and for the purpose described.

2. In a windmill, the combination of the fixed inner vertical shaft carrying the exterior driving-shaft provided with a bevel-gear at 85 top, and a revolute hub mounted on said inner shaft above the driving-shaft and having diametrically-opposite arms, with the oppositely-facing wheels loosely mounted on the arms of said hub and provided with bevel-gears 90 on their inner ends for engaging the gear of the driving-shaft and rotating the same, and a vane on one of said arms outside its wheel, all substantially as specified.

3. The combination, with the main support- 95 ing-shaft A, the hollow shaft F, and its gear f, mounted thereon, of the hub C, having opposite arms E E, journaled on shaft A above shaft F, with the opposite wind-wheels G, loosely mounted on arms E E, and provided with gears 100 for engaging the gear f, each of said wheels being longitudinally adjustable on its arm E, all constructed and arranged to operate substantially as described.

4. In a windmill, the combination, with the 105 revolute support for the wind-wheels, of the vane L, composed of an inner fixed portion, l, mounted upon the wheel-support outside the wheel, and an outer enlarged portion, M, hinged to part l, as described, and the devices 110 for shifting part M, consisting of the hinge O on part M, the pivoted lever P on part l, the connecting-link between said lever and hinge, and the actuating-rope for said lever, and the controlling-spring R, for the parts of the vane, 115 all constructed and arranged to operate substantially as set forth.

In testimony that I claim the foregoing as my own I affix my signature in presence of two witnesses.

ISAAC L. PFAFF.
